UNITED STATES PATENT OFFICE.

FLOYD C. FURLOW, OF MONTCLAIR, NEW JERSEY, ASSIGNOR TO OTIS ELEVATOR COMPANY, OF JERSEY CITY, NEW JERSEY, A CORPORATION OF NEW JERSEY.

COMBINED ELECTRIC-BRAKE AND PUSH-BUTTON PLUNGER-ELEVATOR SYSTEM.

No. 907,986.

Specification of Letters Patent.

Patented Dec. 29, 1908.

Application filed January 8, 1907. Serial No. 351,363.

To all whom it may concern:

Be it known that I, FLOYD C. FURLOW, a citizen of the United States, residing at Montclair, in the county of Essex and State 5 of New Jersey, have invented a new and useful Improvement in a Combined Electric-Brake and Push-Button Plunger-Elevator System, of which the following is a specification.

10 My invention relates to hydraulic elevators, and one of its objects is the provision of an improved automatic push-button electric system of control for hydraulic elevators.

15 A further object of the present invention is the provision of an automatic push-button electric system of control in combination with brake apparatus for plunger elevators.

20 More particularly it is one of the objects of this invention to provide in combination with a push-button controlled plunger elevator system, electric brake apparatus for the plunger to positively hold the car stationary at a desired landing.

25 Other objects of the invention will appear hereinafter, the novel combinations of elements being pointed out in the appended claims.

In the accompanying drawing, Figure 1 represents more or less diagrammatically an 30 automatic push-button controlled elevator system with electric brake apparatus applied to the plunger; Fig. 2 represents in plan and horizontal section, a modified form of brake device; Fig. 3 shows a trip switch in elevation; and Figs. 4 and 5 are detail views of the floor switches.

Similar characters of reference are applied to the two views.

Referring to Fig. 1, C designates an elevator car which is attached to and supported by the plunger P, the latter being arranged to move up and down in the cylinder 1 in the well known manner. To the top of the car C is secured the counterweight rope 2, which 45 passes upwardly over the sheave S to the counterweight W in the usual manner.

V designates a limit stop valve which is automatically operated at the upper and lower limits of travel of the car by the latter 50 striking against the stop buttons or balls B and moving the operating rope R in one direction or the other. The rope R is passed one or more times around the sheave 4 so that when said rope is moved, the sheave 4 55 will be turned to operate the gear mechanism

connected to the pinion 7, which in turn actuates the rack 8 to move the valve 68 in the proper direction to effect a cutting off of the supply or exhaust and thus stop the car. A rope 5 is connected to the sheave 4 at one 60 end and to its other end is connected a weight 6, so that when the car is moved away from its limit of travel, the automatic valve V will be restored to its normal position as shown in Fig. 1.

The apparatus thus far referred to is of well known construction and is here set forth merely by way of illustration, and any other mechanism than that shown may be used if desired. That is, I do not desire to be 65 limited to any particular type of hydraulic elevator as one of the features of my invention is adapted to be combined with any hydraulic elevator in which motor-fluid in the form of liquid or gas must be controlled.

9 and 10 designate, respectively, the supply 70 controlling valve apparatus and the exhaust controlling valve apparatus, the operation of each of which is controlled by the electro-magnetic valve apparatus 11 shown in enlarged view in detail in my copending application, Serial No. 313,540, filed April 25, 1906, push-button controlled plunger elevator system.

The valve devices 9 and 10 comprise differential pistons and are normally held by pressure from constant supply pipes 56 and 56' in the positions indicated in Fig. 1. In addition to these valve devices there is also the automatic stop valve device V which is connected 85 to the cylinder head H by means of the pipe 3. The casings of the auxiliary valves are connected to the upper and lower portions of the casing of the stop-valve device V. The function of the latter is to automatically shut off the flow of water to and from the cylinder 1 when the car approaches either terminal, and it is controlled directly and automatically by the movement of the car in the elevator well, thus making a positive stop in case of 90 derangement of the electrical apparatus.

The main controlling valves 9 and 10 are both normally closed thus cutting off the ingress of water to, or the egress of water from the elevator cylinder 1. When either of the 105 solenoids 25, 26 controlling the auxiliary or pilot valves 51, 51', receives current, the core of the solenoid is lifted with the result that the two-way valve 9 or 10 connected thereto is opened to permit the passage of water to or 110

from the cylinder 1, depending upon whether the car is to go up or to go down. The operating valve remains open and the car continues in motion until the circuit including the operated solenoid is broken by means of one of the floor switches 13, 14, or 15. These switches are used for shifting the current to either the up or down pilot valve, and also for breaking the circuit controlling the electrical apparatus used in connection with the floor at which the switch is located. These switches may be of any desired construction and I show preferred forms in Figs. 3 and 4. These floor switches each comprise a forked arm 101, which is mounted on a fixed pivot 102 in the hatchway. In Fig. 3 is shown an intermediate limit switch which comprises two blades 103 and 104, one of which is always in engagement with the spring clips 105 or 105', as more clearly shown in Fig. 4. Preferably some arrangement is made for holding one of the blades in circuit-closing position, as for example, a spring 118, mounted on a rod 119, which is pivoted at 120 to a spring-operated slide 121. Any other suitable device for holding the blade 103 or 104 in its circuit-closing position may be used, however, if desired.

As will be seen in Fig. 4, the arms 105 are spring-pressed, and mounted so as to be insulated from each other, and have connected to their inner ends the wires 112 and 113, or the wires 122 and 123, as shown in Fig. 4.

Secured to the car C is a cam 16 which carries a laterally projecting pin 100. This pin is arranged to engage the fork or butterfly 101 of the intermediate switch, as that designated 14, and thus reverse the positions of the blades. This pin 100 may also be depended upon for operating the top and bottom floor switches 13 and 15, but I may operate the latter by means of the cam 16 striking against an arm carrying a roller at its outer end and being fixed to the shaft which carries the switch blade at its other end. When the switches 13 and 15 are thus operated, their knives are pulled out of contact with the clips, thereby breaking the circuit. When this occurs the core of the solenoid and stem of the auxiliary valves return to their normal positions by gravity, causing the two-way valve to immediately close and effect a stopping of the car.

The current used for operating the electromagnetic apparatus may be taken from the electric light wires in a building, with resistance, as for example a suitable number of incandescent lamps, inserted to reduce the potential. Obviously, any other source of electric current may be used if desired, as for example, electric batteries, or a dynamo, or an alternating current generator. Although three floor switches are shown, the number may be decreased or increased in accordance with the operation predetermined upon.

Referring now to the wiring for controlling the pilot valve mechanism 11 and the trip switches 12, it will now be explained how the push-buttons when operated, are automatically thrown out or short-circuited as soon as one of the trip switches 12 has been actuated. It will be seen that as soon as a push-button at a landing or one of the push-buttons in the car, has been operated, the operator is given exclusive control of the car, and the latter will go to the selected landing unless the safety switch in the car is operated, in which case the car would be immediately stopped.

It should be noted that an up or "call" push-button is provided at each floor, and that in addition thereto, there is also a down or "return" button at each floor. These sets of push-buttons or switches are designated 17, 18 and 19 in Fig. 1. The up or call button brings the car automatically to the floor where operated, while the down or return button, which is connected in parallel with the basement call button 19, enables a person, after using the elevator, to cause it to return to the first floor if desired.

In the car is a set of push-buttons numbered to correspond with the several floors, each button being wired in parallel with the corresponding floor call button or switch. Controlled by the doors leading into the elevator well or shaft are the respective door switches 20, 21 and 22. These switches are all in the same circuit and in this circuit is a stop push-button or safety switch 24, which enables a passenger to break the circuit at will to effect the stopping of the car at any desired position in the elevator well or hatchway, or at any time.

The operation of the construction thus far disclosed will be understood from the following explanation. Assuming that the car is at an intermediate floor and that the push-button 71 at the top floor be operated so as to close the circuit from the + main through one blade of the main line switch 72, and thence by way of wire 73, door contacts 22, 21 and 20, wire 74, safety switch 24 in the car, wire 75 to the trip switches 12. These trip switches are in such a position normally, that the circuit will continue through the stationary contact strips 83 and connecting wires 84, to the wire 85, and thence the circuit continues through conductor 86, push-button 71, conductor 87, electro-magnet 89, conductor 90, switch 13, which at this time is in a closed position, conductor 91, solenoid 25, conductor 92, and finally through the other blade of the main line switch 72 to the - main. It will be noticed that this circuit includes the coil of the lowermost electro-magnet 89 and the electro-magnet 25.

One of the trip switches is shown in elevation in Fig. 3, and comprises a base or support 77 on which are mounted the electro-

magnet 89 and the table 78. The latter carries a bracket 95 on which is pivoted at 94 an armature 93, the outer end of which carries a piece of insulation 96. On the right-hand 5 end of the table 78, as viewed in Fig. 3, is secured a block of insulation 80 which carries contacts 83, 79 and 97, and also supports a spring 82 which acts on one end of the circuit-closing bar 76. With the other end of 10 this bar is associated a spring 81 which acts to move the inner end of the bar 76 so as to electrically connect the contacts 83 and 79. The spring 82 at this time acts upwardly at 15 the other end of the bar 76 to move the same out of engagement with the contact 97. The electrical connections of the wiring with these contacts will be clear from an inspection of Fig. 1.

When the electro-magnet 89 is energized 20 and the armature 93 is actuated, the block of insulation 96 is moved upwardly and strikes against the inner end of the circuit-closing bar 76, and disengages the same from the contact 79. This operation, however, effects 25 the engagement of the bar 76 with the contact 97 but the contact 83 is still in electrical connection with said bar 76. The upward movement of the insulation 96 may be regulated by the set screw 143 which may also 30 serve to prevent sticking of the armature to the poles of the magnet if said set screw is made of non-magnetic material. The spring 81 being stronger than the spring 82 will restore the parts to normal position when the 35 magnet is de-energized, the downward movement of the insulation being limited by the abutment 144 with which may be associated a restoring spring if desired.

When one of the electro-magnetic switches 40 12 is operated all of the push-buttons 17, 18 and 19 at the landings and the push-buttons 23 in the car will be short-circuited so that even if they were operated after the car has been started in motion, they could have no 45 effect whatever until the car has reached the floor to which it has been sent or called, and the relay device shown in Fig. 3 automatically restored to its normal position, which is that shown in said figure. The holding or 50 retaining circuit of the electro-magnets 89 and 25 excluding the push-buttons, may be traced from the + main to and through the wire 73, door switches 22, 21 and 20, wire 74, safety switch 24 in the car, conductor 75, 55 contact 83, bar 76, contact 97, conductor 98, conductor 99, lowermost magnet 89, conductor 90, switch 13, conductor 91, magnet 25, and conductor 92 to the - main.

It will be noticed that a separate relay is 60 used for each floor, that is, if there are three floors, as shown, there should be three relays. A separate magnet is of course used for each switch, the coils of such magnets taking their current from the same trip 65 switch that the magnet governs, and are con-

nected with floor buttons or switches so that the circuit through any magnet may be closed by operating the corresponding floor push-button connected with the same. The current then passes on through the corresponding floor switch to one of the solenoids operating the auxiliary or pilot valves, and thence to the return wire as traced above. Assuming again that the solenoid 25 receives current and its core 37 together with the parts connected thereto, are lifted the auxiliary or pilot valve 51 will be opened to permit the motor-fluid to pass from the supply pipe 27 into the pipe 31 and thence to the chamber 54 to act on the piston 55 to move it downwardly against the action of the motor-fluid in the chamber 57 connected with the constant pressure supply pipe 56.

It will be noticed that the pistons 55 and 58 are of different dimensions, the latter being smaller, and both being secured to the valve stem 59 which carries at its lower portion the piston valve 60 and the piston 61. The latter is arranged to move in the chamber 63 and is retarded in its upward direction 90 by the check valve 62 so that the valve 60 will close slowly but may be moved in the opposite direction to open said valve quickly. This has the effect of letting the supply pressure from the pipe 52 into the plunger cylinder 1 quickly and thus obtaining a quick start of the elevator car. In order, however, to prevent the car from stopping too suddenly, the valve 60 should be closed slowly and this may be accomplished by restricting 95 the flow of air into the chamber 63 through the check valve 62 in any well known manner.

The electro-magnet solenoid 25 having lifted its core or plunger 37 and operated the valve 51 to effect a downward movement of the piston 55 by its differential action, the valve 60 will be moved downwardly quickly and the main supply fluid flow from the pipe 52 past the valve 60, and thence through the 105 pipe 64, port 65, chamber 70, and connecting pipe 3, to the plunger cylinder 1, or to the piston cylinder in case a hydraulic elevator system of the car suspension type is employed.

The valve 9 having been opened and the supply pressure communicated to the plunger P, the car will be moved upwardly until it arrives at its designated landing, when the pin 100 will operate the switch 13 to effect a de-energization of the magnet solenoid 25 and the consequent closure of the pilot valve 51. The supply pressure from the pipe 56 will now effect a return of the valve 60 to a closed position slowly and the fluid in the chamber 54 will be exhausted through pipe 31, pilot valve 51, and exhaust pipe 28, the piston 60 being retarded by an adjustable opening in the check valve 62, as heretofore explained.

The car will go to the uppermost landing and operate the switch 13 to open the same and thus stop the car but if the car should go beyond this point for any reason whatever, the stop-ball B would be struck and the drum or sheave 4 turned by means of the rope R to move the valve 68 upwardly and close communication between the valve 9 and the pipe 3.

10 It will be noticed that the stop-valve V comprises the balanced pistons 67, 68 and 69 so that the fluid pressure acting thereon will have no tendency to move the same. Inasmuch as the communication between the 15 supply pipe 52 and pipe 3 to the cylinder 1 is thus closed by the stop valve, and the valve 10 is closed, the elevator car will come to a positive stop at its uppermost limit of travel.

20 The path of the current for the floor switch 13, 14 or 15 to the up or down auxiliary pilot valve solenoids 25 or 26, depends entirely upon which line the contact blades of the intermediate floor switch are connected with, this in turn depending upon the 25 location of the car. Thus when the car passes the intermediate floor switch on its upward movement, it sets it to next direct the current to the exhaust or down magnet 30 solenoid, and when it passes this floor switch on its downward movement, it sets it to next direct the current to the supply or up valve magnet. At an intermediate position of the switch 14 both circuits are broken, so that at 35 each passage of the car the floor switch is thrown out before being reversed. When the floor switch through which the current is flowing is thus thrown out, the current is cut off from the controlling magnet 89, and from 40 the auxiliary pilot valve solenoid 25 or 26, thus causing the main valve to close and stop the car.

The return movement of the armature 93 of the controlling magnet 89, when the current is cut off, allows the trip switch to return to its normal position again connecting up the series of automatic switches ready for the next movement.

It should be noted that after the operator 50 at a landing or in the car has once pushed a button or operated a switch, it is unnecessary to hold the switch closed, for as soon as the magnet controlling the trip switch has been operated, the push-button circuit is entirely 55 thrown out of operation, that is, it is short-circuited as hereinbefore explained. It will also be seen that since the push-button circuit is made inoperative after the car has once been set in motion, it is impossible for 60 anyone else to get control of the car until it has reached the desired floor and come to a full stop. If two buttons are pushed at almost the same time, the car will respond to the first call, although the two calls may be 65 but a fractional part of a second apart. It

should furthermore be noted that the system herein disclosed has a high degree of safety, and it can readily be seen that an accident, so far as a confusion of calls is concerned, is practically impossible, for as soon as the car reaches a floor and the door is opened, it is impossible to start the same again from any floor or from within the car, until all the doors leading to the elevator well are in a closed position and the door contact switches 70 20, 21 and 22 are also closed. In connection with this system any approved door lock which securely locks the doors until the car is substantially level with the floor landing, may be used if desired.

Assuming that the car is at its uppermost landing, and the floor switch 14 is in the position shown in Fig. 4, so as to electrically connect the conductors 112 and 113, let it be desired to call the car to the 85 floor below. In this case the push-button 116 is operated, whereupon a circuit will be established from the + main to and through the wire 73, door contacts 22, 21 and 20, conductor 74, safety switch 24 in 90 the car, conductor 75, contacts 83 and connecting conductors 84, conductors 85, 86, push-button 116, which has been operated, conductors 137, 117, magnet 89 (second in 95 the series), conductor 114, wire 113, switch 100 blade 104, and spring-pressed contacts 105, conductors 112, 115, down magnet 26, and conductor 92 to the - main. Pilot valve 51' will thereupon be operated and the middle trip switch operated to short-circuit 100 the push-buttons at the landings and the push-buttons 23 in the car.

Pilot valve 51' having been opened, the fluid under pressure will flow through the pipe 32 to the chamber 54' of the valve 10 and effect a movement of the valve 60' to its open position. The valve 9 is at this time in the position shown in Fig. 1, and so also is the stop valve V. The opening of the valve 60' establishes connection between the cylinder 1 and the exhaust pipe 53. The car may therefore descend in the well known manner until the pin 100 strikes the fork or butterfly 101 to disconnect the wires 112 and 113 and thus 115 effect a deenergization of the magnet solenoid 26. The pilot valve 51' will thereupon be closed by reason of gravity acting on its moving parts, and the constant pressure supply from the pipe 56' will effect 120 a return of the valve 60' slowly to its normal or closed position, thus stopping the car at the desired landing.

If the car arrives at the lowermost landing, it will operate the switch 15 which also 125 cuts off current from the solenoid 26 and effect the stopping of the car in the same manner. If the lower stop button B is actuated the valve 68 will be moved downwardly to automatically cut off the 130

exhaust flow from the cylinder 1 to the exhaust pipe 53, and thus stop the car.

It will be noticed that also the valve 10 is provided with a small check valve 62' 5 so that the valve 60' may be opened quickly and therefore the car will be allowed to start downwardly quickly and to close slowly so that the car will stop gradually.

The apparatus thus far described is the same as disclosed in my co-pending application already referred to. It should be noted that it is one of the especial objects of my invention to provide means for positively holding the car stationary in a desired position, as at a landing, so that there may be no settling and consequent derangement of the circuits and connections of the push-button systems. This I deem a valuable feature of my invention, 20 as without it, an automatic push-button controlled elevator system would be impracticable by reason of movement of the car away from the landing due to leakage of the motor-fluid from the plunger cylinder 25 and the consequent irregular stopping of the car near other landings. I have in my co-pending application referred to, illustrated the brake apparatus disclosed and claimed in my Patent No. 810,404, granted 30 January 23, 1906, for an improvement in retarding devices for plunger elevators, while in the accompanying drawing I have illustrated an electro-mechanical brake. I do not, however, claim as my invention the 35 electro-mechanical brake apparatus *per se* comprising an electro-magnet, brake shoes and springs associated with a plunger of a plunger elevator, as such is the invention of Mr. W. D. Baldwin and covered in his 40 pending application, Serial No. 231,257, filed November 3, 1904, for an improvement in retarding device for plunger elevators. So far as this particular feature of my invention is concerned, any other 45 system of automatic push-button control than that illustrated may be used in combination with brake apparatus for the plunger.

The brake apparatus illustrated in Fig. 1 50 comprises a magnet solenoid 133' in this instance connected rigidly to the cylinder head H. Freely movable within this solenoid is a core or armature 156 to the upper end of which is connected the stem 137. This in 55 turn is connected by the link 138 to the brake lever 139 which is rigidly connected to the cam member 140 between the crossed brake shoes or gripping devices in contact with the plunger. The cam 140 is pivoted at 141 to 60 the support 157 mounted on top of the cylinder head H. When the solenoid 133' receives sufficient current the core 156 will be lifted and so also the parts connected thereto so as to release the gripping jaws and permit 65 the plunger to be moved. When the current

is cut off the weight of the core 156 will effect the application of the brake, or if this is not sufficient, the weight 159 may be placed on an extension of the lever 139. A stop 158 may be placed in proper position to limit the 70 downward movement of the lever 139 and hold the same where the cam 140 will have maximum effect in applying the jaws firmly to the plunger.

In Fig. 2 I have shown a modified brake 75 apparatus in that the solenoid 133' is arranged horizontally instead of vertically, and has two cores 160, 160' which are connected by the stems 161, 161' to the levers 162, 162' pivoted at 163, 163', respectively. The other 80 ends of these levers are associated with the brake rods 164, 164' which are connected to the brake shoes 165, 165', respectively.

It will be seen that in this instance the brake rods 164, 164' pass through the cylinder head H' which is provided with suitable recesses 167, 167' for receiving the brake springs 166, 166'. The brake is therefore applied practically inside of the hydraulic cylinder. It should be understood, however, 85 that the brake apparatus may be entirely outside of the cylinder 1 by providing suitable supports outside the cylinder for the various parts.

With the construction shown in Fig. 2 it 95 should be noted that when the solenoid 133' receives sufficient current, the cores 160, 160' are drawn inwardly to actuate the levers 162, 162', the brake rods 164, 164' and the brake shoes 165, 165' against the action of the 100 springs 166, 166'. When the shoes are released the plunger may be actuated and when the current is cut off the springs again apply the shoes to the plunger to retard the 105 the same and thus assist in the stopping thereof and to hold the plunger stationary after being stopped.

The brake magnet may be controlled by any suitable electric switches actuated preferably by some moving part of the valve 110 apparatus. In this instance I have shown the switches 168, 168' above the pilot valve magnets to be actuated thereby. The contact members 169, 169' are yieldingly connected to the upper ends of the plunger 115 stems 172, 172' by means of the springs 170, 171 and 170' and 171', respectively. Normally the connecting members 169, 169' respectively rest on the fixed contacts 173, 174 and 173', 174', and the circuit of the solenoid 120 of the brake magnet is open.

When the solenoid 25 receives current to open the pilot valve 51 the contact member 169 is lifted to disconnect the contacts 173, 174 and to electrically connect the fixed 125 contacts 175, 176, a short distance above. A circuit is then completed to effect the release of the plunger brake. This circuit may be traced from the + main through the upper blade of the main line switch 72, conductors 130

73, 177, contact 175, bridge piece 169, contact 176, conductors 178, 179, 136', solenoid 133', conductors 135', 92, lower blade of the main line switch, to the - main. The solenoid 133' being thus connected directly across the mains receives full power and in a short space of time depending upon the time constant of the brake magnet the brake will be released. At about the same time that the brake is being released the valve 9 is being opened quickly so that the car is at once lifted and brought to full speed without delay. Now when the current is cut off from the solenoid 25 to effect the stopping of the car, the bridge piece 169 will drop also cutting off the current to the brake magnet. It is preferred to stop the car gradually, however, so the brake should not be applied too suddenly but should be permitted to be applied gradually. This may be accomplished in various ways. In this instance I have associated electric switches 180, 180' with the valves 9, 10, respectively, and provided a resistance 172 arranged to be inserted in circuit with the brake magnet solenoid to effect only a partial application of the brake to assist in stopping the car until the valve 9 or 10 is closed or nearly so when the brake is fully applied.

30 When the bridge piece 169 drops to connect the contacts 173 and 174 while the bridge piece 181 still connects the contacts 184 and 185, the resistance 172 will be inserted in circuit with the solenoid 133' of the brake magnet. This resistance may be of any desired magnitude so as to decrease the power of the electro-magnet to any desired extent and thus secure a retarding action of the brake in accordance with the closing 40 movement of the valve device 9. This circuit may be traced from the positive main through the conductors 73 and 177, resistance 172, contact 173, bridge piece 169, contact 174, conductor 186, contact 185, bridge piece 181, contact 184, conductor 136', solenoid 133', conductors 135', 92, out to the - main. As soon as the valve 60 has been moved down so that the nut on the outer end of the stem 183 positively engages the bridge piece 181, the contacts 184 and 185 will be electrically disconnected and the brake solenoid circuit entirely opened. The weight 159 will thereupon fully apply the brake to the plunger P substantially at the same time or preferably a short time before the supply through the valve device 9 is entirely cut off.

When the contact member 169' returns to its lower position as shown in Fig. 1, and the switch 180' is still closed, the resistance 172 will also be inserted in circuit with the solenoid 133', this circuit extending from the positive main through the conductors 73, 177, resistance 172, conductor 187, contact 173', bridge piece 169', contact 174', conductor 188, contact 185', bridge piece 181', contact

184', conductors 189, 136', solenoid 133', conductors 135', 92, out to the negative main. As soon as the valve 60' has been moved downwardly to a certain degree so that the bridge piece 181' merely rests on top of the spring 182' and the contacts 184' and 185' are disconnected, the brake will be fully applied by reason of the entire deenergization of the brake magnet. As heretofore explained, it is preferable that the valves 60 and 60' close slowly so as to bring the elevator car to a gradual stop whether it is traveling upwardly or downwardly. It is evident that the partial application of the brake to the plunger assists in thus gradually stopping the car and relieves the strain on the valve apparatus. Preferably the switch 180' is so adjusted that the brake will be fully applied at about the same time or a brief space of time before the valve 60' is closed.

Obviously those skilled in the art may make various changes in the details and arrangement of parts without departing from the spirit and scope of my invention, and I desire therefore, not to be limited to the precise construction herein disclosed.

Having thus fully described my invention, what I claim and desire to have protected by Letters Patent of the United States is:—

1. The combination with a load-carrying device, a plunger and operating apparatus, of brake mechanism for said plunger, and electric circuits and connections to automatically control said operating apparatus and said brake mechanism to cause said load-carrying device to start from any position and stop at a predetermined position.

2. In a hydraulic elevator, the combination with a plunger and a car, of a retarding device for the plunger, and an electro-magnet controlled from the car or from a landing for effecting the release or application of said retarding device.

3. In a hydraulic elevator, the combination with a car, a plunger and change-valve apparatus, of a retarding device, a motor for operating said retarding device independently of said change-valve apparatus, and a single device for controlling both the change-valve apparatus and said motor to cause the car to stop at any selected point intermediate its limits of travel.

4. In a hydraulic elevator, the combination with a plunger and change-valve apparatus, of a retarding device, a motor for operating said retarding device, and a plurality of pilot valves each controlling the operation of both the motor and the change-valve apparatus.

5. In a hydraulic elevator, the combination with a car, a plunger and change-valve apparatus, of a retarding device, a motor for operating said retarding device independently of said change-valve apparatus, and

means controlled from the car or from a landing for effecting the operation of both the change-valve apparatus and the said motor.

6. The combination with a plunger elevator, of valve mechanism for controlling the same, a retarding device for the plunger, electric appliances for controlling said valve mechanism, push-buttons connected to said electric appliances, and means for cutting out the circuits of all the push-buttons after one has been operated to effect the starting of the car to a selected point corresponding to the operated push-button and the automatic operation of the retarding device upon 10 approaching such point.

7. The combination with a plunger elevator and hydraulic mechanism for controlling the operation of the same, of electric circuits and connections of an automatic push-button 20 ton controlling system for said hydraulic mechanism, a brake for the plunger, and means operated by the car for automatically arresting the same at a predetermined point by cutting off the motive power and effecting 25 the application of said brake.

8. The combination with a plunger elevator and hydraulic mechanism for controlling the operation of the same, of a retarding device for the plunger, electric means for controlling said hydraulic mechanism and said retarding device, push-buttons or switches connected to said electric means, and appliances for rendering all of the push-button circuits inoperative while the car is in motion.

9. In an elevator, the combination with a car, of a plunger connected thereto, controlling apparatus, a push-button controlled electric system for operating said controlling apparatus, and means applied to the plunger for positively holding the car stationary, said means being dependent for its operation upon said push button controlled electric system.

45 10. In an elevator, the combination with a car, of a plunger connected thereto, controlling apparatus, a push-button controlled electric system for operating said controlling apparatus, and means connected to said controlling apparatus and associated with said plunger for holding the car in a fixed position.

11. In an elevator, the combination with a car and a plunger, of valve apparatus for controlling the movements thereof, an automatic push-button controlled system of electric circuits and connections for effecting an automatic stop of said car at a predetermined landing, and a brake associated with 55 the plunger to positively retard the motion of the car and plunger and hold the same substantially stationary at a landing.

12. In a hydraulic elevator, the combination with a car and a plunger, of a retarding device for such plunger, and means controlled

from the car or from a landing for releasing said retarding device.

13. In a hydraulic elevator, the combination with a car and a plunger, of a retarding device for such plunger, and electro-mechanical means within the control of the passenger in the car or at a landing for releasing and applying such retarding device.

14. In a hydraulic elevator, the combination with a plunger and a car, of a retarding device for the plunger, and automatic electro-mechanical means controlled from the car or from a landing for starting and stopping said car and for releasing and applying said retarding device.

15. In a hydraulic elevator, the combination with a plunger, of a car connected to the plunger, valve apparatus, a retarding device for the plunger, actuating means for said retarding device, and electro-mechanical appliances for operating said valve apparatus and said actuating device.

16. In a hydraulic elevator, the combination with a plunger, of reversing valve mechanism for controlling the movement of said plunger, a retarding device for the plunger, a motor for operating said retarding device, and electro-mechanical means for effecting the operation of said reversing valve mechanism and of said motor.

17. In a hydraulic elevator, the combination with a plunger and a car, of a retarding device for the plunger, a motor for operating said retarding device, and electro-mechanical means for controlling the starting, stopping and the reversing of the movement of the car and substantially at the same time the operation of said motor.

18. In a hydraulic elevator, the combination with a plunger and a car, of a brake for said plunger, means for controlling the movement of the car, a motor for operating said brake, and electro-mechanical apparatus for effecting the operation of said controlling means and of said motor to release and apply said brake.

19. In a hydraulic elevator, the combination with a plunger and a car, of a brake for the plunger, a motor for operating said brake, reversing valve mechanism for controlling the movements of the car and plunger, pilot valve apparatus for controlling said reversing valve mechanism, and electric means for operating said pilot valve apparatus and for controlling said motor.

20. In a hydraulic elevator, the combination with a plunger and a car, of a cylinder for said plunger, means for controlling the flow of fluid to or from said cylinder, a brake for the plunger, a motor connected to said brake, pilot mechanism connected to said controlling means and to said motor, and electro-magnetic means for operating said pilot mechanism.

21. In an elevator, the combination with a

car, of a plunger connected thereto, controlling apparatus, a push button electric system for operating said controlling apparatus, and electro-mechanical means controlled by said 5 push-button electric system and associated with the plunger for positively holding the car stationary.

22. In an elevator, the combination with a car, of a plunger connected thereto, controlling apparatus, a push button controlled electric system for operating said controlling apparatus, a brake associated with the plunger, and electric means connected to said 10 controlling apparatus for controlling the operation of said brake.

23. In an elevator, the combination with a car, of a plunger connected thereto, valve apparatus for controlling the movements of said plunger, electric means for operating 20 said valve apparatus, a brake associated with the plunger, an electro-magnet for controlling the operation of said brake, and electric switches associated with said electric means for controlling said electro-magnet.

24. In an elevator, the combination with a car and a plunger, of valve apparatus for controlling the movements thereof, an automatic push button controlled system, circuits and connections for effecting an automatic stopping of said car at a predetermined landing, and electro-mechanical brake apparatus associated with the plunger to 30 positively retard the motion of the car and plunger and hold the same substantially stationary at a landing.

25. In a hydraulic elevator, the combination with a car and a plunger, of a retarding device for said plunger, and electric means controlled from the car or from a landing for 40 releasing said retarding device.

26. In a hydraulic elevator, the combination with a car and a plunger, of a retarding device for such plunger, and an electro-magnet within the control of the passenger with 45 in the car or at a landing for releasing and applying such retarding device.

27. In a hydraulic elevator, the combination with a plunger and a car, of a retarding device for the plunger, and an electro-magnet 50 net controlled from the car or from a landing for effecting the release or application of said retarding device.

28. In a hydraulic elevator, the combination with a plunger and valve apparatus, of 55 a retarding device associated with the plunger, an electro-magnet connected to said retarding device, and means for effecting the energization of the electro-magnet to release the retarding device upon the operation of 60 said valve apparatus to effect the starting of the car.

29. In a hydraulic elevator, the combination with a plunger, of a car attached to the plunger, valve apparatus, a retarding device 65 for the plunger, actuating means for apply-

ing said retarding device to the plunger, an electro-magnet connected to said retarding device to release the same against the action of said actuating means, and electro-mechanical means for operating said valve apparatus and said electro-magnet. 70

30. In a hydraulic elevator, the combination with a plunger, of reversing valve apparatus for controlling the movement of said plunger, a retarding device for the plunger, 75 an electro-magnet for operating said retarding device to release the same, and electro-mechanical means for effecting the operation of said reversing valve apparatus and the energization of said electro-magnet. 80

31. In a hydraulic elevator, the combination with a plunger and a car, of a retarding device for the plunger, means for actuating said retarding device to apply the same to the plunger, an electro-magnet for releasing 85 said retarding device, and electro-mechanical means for controlling the starting, stopping and the reversing of the movement of the car, and substantially at the same time, the energization of said electro-magnet. 90

32. In a hydraulic elevator, the combination with a plunger and a car, of a gripping device for said plunger, an electro-magnet for actuating said gripping device to release the same, and electro-mechanical means for 95 controlling the operation of the plunger and the energization of said electro-magnet.

33. In a hydraulic elevator, the combination with a plunger and a car, of a brake for said plunger, means for controlling the movement of the car, brake-applying means, electric brake-releasing means, and electro-mechanical apparatus for effecting the operation of said controlling means and of said electric brake releasing means. 100

34. In a hydraulic elevator, the combination with a plunger and a car, of a brake for the plunger, brake-applying means, an electro-magnet for actuating said brake-applying means to release the brake, reversing 110 valve mechanism to control the movements of the car and plunger, pilot valve apparatus for controlling said reversing valve mechanism, electric means for operating said pilot valve apparatus, and switches associated 115 with said electric means for controlling the operation of said electro-magnet.

35. In a hydraulic elevator, the combination with a plunger and a car, of a cylinder for receiving said plunger, means for controlling the flow of fluid to or from said cylinder, brake mechanism for the plunger, an electro-magnet for controlling said brake mechanism, pilot mechanism connected to said fluid 120 controlling means, electro-magnetic means for controlling said pilot mechanism, and electric circuits and connections for effecting the operation of said electro-magnetic means and the energization of said electro-magnet. 125

36. In a hydraulic elevator, the combina- 130

tion with a plunger and a car, of a plurality of brake shoes associated with the plunger, means for applying said brake shoes to the plunger, an electro-magnet for releasing said brake shoes from the plunger, valve apparatus for controlling the movements of the car and plunger, and automatic push button controlled apparatus for controlling said valve apparatus and said electro-magnet.

37. In a hydraulic elevator, the combination with a plunger and car, of a cylinder for receiving said plunger, valve apparatus for controlling the flow of fluid to and from said cylinder, pilot mechanism for controlling valve apparatus, electro-magnets for controlling said pilot mechanism, a brake, brake-applying means, an electro-magnet to effect the release of the brake, and circuits and connections of an automatic push-button controlled electric elevator system for controlling the pilot mechanism electro-magnets and the brake electro-magnets.

38. The combination with a plunger of a plunger elevator system, of electro-magnetic brake apparatus associated with said plunger, and means for partially deenergizing the brake magnet to effect a partial application of the brake on the plunger when the car comes to rest.

39. The combination with a plunger and a car, of a cylinder for receiving said plunger, valve apparatus for controlling the flow of fluid to and from the plunger, electro-magnetic brake apparatus associated with the plunger, and means co-acting with the valve apparatus for effecting only a partial application of the brake to the plunger as the car is coming to rest.

40. The combination with a car and its plunger, of a cylinder for receiving said plun-

ger, of reversing valve mechanism, connected to the cylinder, a brake associated with the plunger, means for applying said brake to the plunger, an electro-magnet for actuating said brake applying means to release the brake, 45 and automatic means associated with said reversing valve apparatus to effect the insertion of resistance in circuit with said electro-magnet until the reversing valve apparatus has been operated to a predetermined extent 50 in bringing the car to rest.

41. In a hydraulic elevator system, the combination with a car and moving means therefor, of valve apparatus for controlling said moving means, a brake associated with 55 a part moving in harmony with the movement of the car, brake-applying means, an electro-magnet connected to said brake-applying means to actuate the same and effect the release of the brake, a resistance, and 60 electric switch mechanism connected to said valve apparatus to effect the insertion of said resistance in circuit with said electro-magnet while said valve apparatus is being closed to a predetermined extent and the car is being 65 stopped.

42. In an elevator, the combination with a car, of a plunger connected thereto, valve apparatus for controlling the movement of the plunger, electric means for operating said 70 valve apparatus, and means connected to said valve apparatus for positively holding the plunger and car in stationary position.

In testimony whereof, I have signed my name to this specification in the presence of 75 two subscribing witnesses.

FLOYD C. FURLOW.
